UNITED STATES PATENT OFFICE.

WILLIAM ANDERSON, OF HULTON, PENNSYLVANIA.

DESIGN FOR A MANTEL.

SPECIFICATION forming part of Design No. 19,876, dated June 3, 1890.

Application filed March 17, 1890. Serial No. 344,228. Term of patent 7 years.

To all whom it may concern:

Be it known that I, WILLIAM ANDERSON, a citizen of the United States, residing at Hulton, in the county of Allegheny and State of Pennsylvania, have invented certain new and useful Improvements in a Design for Mantels; and I do hereby declare the following to be a full, clear, and exact description of the invention, such as will enable others skilled in the art to which it pertains to make and use the same, reference being had to the accompanying drawings, which form a part of this specification.

In the accompanying drawings, Figure 1 is front elevation of a mantel showing my design. Fig. 2 is a sectional elevation of the same, these two views being deemed necessary to illustrate my design.

In the drawings, *a* represents the pilasters, which extend from the hearth to the mantel-board *b*, and are provided with caps *c* on the top and bottom, and with beveled edges. Between the top and bottom caps *c* and on the pilasters *a* are strips *f*, having a series of reeds formed along the center of each, and also provided with bevel edges. Beneath the top caps *c* are small corner-pieces *g*. The

frieze *h* has a series of reeds *i* thereon, a lower bevel edge, and a strip *r* of molding beneath the same. The mantel-board *b* has a molded 30 edge and a strip *k* beneath the same and along the top of the frieze, to bring the same flush with the caps *c* to arrange a molding *l* beneath the mantel-board *b*. On each of the top caps *c* are two brackets *m*, having the 35 molding *l* extended about the top of the same. The side strips *n* and fire-strip *o* are each formed with a groove or reed along their front faces.

Having thus described my design, I claim— 40

The design for a mantel herein described and shown, consisting of the pilasters *a*, the caps *c*, the brackets *m*, the facing-pieces *f*, and corner-pieces *g*, the frieze *h*, backing-strip *k*, and molding *l*, the mantel-board *b*, side *n*, 45 and fire-strips *o*, substantially as described.

In testimony that I claim the foregoing I hereunto affix my signature this 8th day of February, A. D. 1890.

WILLIAM ANDERSON. [L. S.]

In presence of—

C. C. LEE,
M. E. HARRISON.
